UNITED STATES PATENT OFFICE.

JOSEPH A. CONRAD, OF BELOIT, WISCONSIN.

SECTIONAL RADIATOR.

Application filed May 23, 1922. Serial No. 563,174.

To all whom it may concern:

Be it known that I, JOSEPH A. CONRAD, a citizen of the United States, residing at Beloit, in the county of Rock and State of Wisconsin, have invented certain new and useful Improvements in Sectional Radiators, of which the following is a specification.

This invention relates to radiators for use with water-cooled internal combustion engines, and has more particular reference to those used on motor vehicles.

The primary object of the present invention is to provide a new and improved radiator especially designed to simplify repairing. The tubes or circulating pipes not infrequently are bursted as a result of freezing, and they are sometimes broken as the result of accident, and in other instances simply by wear of the joints. Heretofore, it has been quite difficult to repair these tubes by reason of the fact that the radiation fins have been soldered or otherwise secured to the tubes, making it difficult to repair and to get to the point of leakage, especially if it is one of the inner tubes of the group. I have overcome the inconvenience attendant upon making these repairs by the provision of a sectional radiator, that is, one having removable sections permitting ready access to the circulating tubes.

My invention also contemplates the provision of a sectional radiator characterized by a tank and tube section, and a removable front casing section carrying radiation fins disposed when in operative position, in front of the circulating tubes. This casing section is designed to have the outward appearance of a conventional radiator, but which is in fact, quickly removable to give ready access to the tubes and to the upper and lower tanks. It will be manifest that inasmuch as all repairs of the tanks or tubes are made when the front casing section is removed, the finish of the latter is not marred by the soldering or other repairing operation. In the preferred embodiment, a back fin section is also employed. Another object is to provide a sectional radiator of the character described constructed in such simple and practical manner as to enable production at a comparatively low cost and which will be thoroughly practical for the purposes intended.

Other objects and attendant advantages

will be appreciated by those familiar with this art as the invention becomes better understood by reference to the following description when considered in connection with the accompanying drawings, in which—

Figure 1 is a perspective view of a sectional radiator embodying my invention;

Fig. 2 is a vertical section through the radiator;

Fig. 3 is a side view partly in section, of the front casing section;

Fig. 4 is a vertical sectional view through the tank and tube section;

Fig. 5 is a vertical sectional view through the back fin section;

Fig. 6 is a horizontal sectional view taken on the line 6—6 of Fig. 4;

Fig. 7 is a front view of the tank and tube section;

Fig. 8 is a front view of the back fin section; and Fig. 9 is an enlarged vertical section through the radiator, similar to Fig. 2.

My invention comprehends, primarily, provision of a radiator comprising a tank and tube section and a front casing section having radiation fins, and I prefer also to employ a back radiation fin section, these to be removably associated so that the front casing section and the back fin section may be quickly and easily removed from the tank and tube section when it is necessary to repair leaks in the latter.

In the preferred embodiment shown, the tank and tube section is made up of upper and lower tanks 9 and 11 respectively, joined by vertical circulation tubes or pipes 12, preferably elongated transversely to the path of air through the radiator and arranged in staggered relation as shown in Fig. 6. This structure has a side 10 and suitable outstanding supporting arms 13 adapted to rest on the frame of a motor vehicle and to be bolted or otherwise secured thereto. Additional means, not shown, may be provided for rigidly securing the upper end of this radiator section in position, such for example, as the usual stay-rod now commonly employed for this purpose. The tank 9 has an inlet or upper hose connection 14 and the tank 11 an outlet or hose connection 15. The upper tank has also a water supply or filling opening 16 adapted to be closed by the usual radiator cap 17. The water or

other cooling liquid enters the tank 9 through pipe hose connection 14 and circulates down through the tubes 12 and thence through the tank and connection 15 in the usual manner, it being manifest that the pipes 14 and 15 are to be connected with the water chamber or jackets of the engine for circulation of the water through the latter. In the preferred embodiment, radiation fins 20 may be interposed between and soldered or otherwise united to the tubes 12 for increasing the radiation efficiency, it being noted that by this arrangement of fins every tube is exposed at one or more sides, as shown in Fig. 6, to facilitate repairing.

The front or outer casing section is shaped to fit over the tank and tube section and to be of pleasing and symmetrical design and 20 enameled or otherwise finished so that when in operative position, it will give the appearance of a unitary radiator structure. In the present case, this casing section comprises a front 18, sides 19, a top 21 and outwardly projecting supporting arms 22 adapted to rest upon the supporting arms 13 and be secured with the latter to the frame structure. In the present instance, bolt holes are provided through the arms 13 and 22 for the reception of retaining bolts. The top wall 21 of the front casing section has an opening 23 for the passage of the upstanding filler mouth or pipe 16. The front wall 18 of said casing has an opening 24 disposed in front of and registering with the circulating tubes 12. This opening is covered by radiation fins 25 disposed at the inner side of said front wall 18 and secured thereto so as to occupy a position directly in front of and in contact with the foremost circulating pipes. Said radiation fins 25 will be held in contact with said circulating pipes by the bolts (not shown) which pass through the arms 13 and 22 and clamp the casing and radiator to the chassis. The fins thus become conductors and serve to radiate heat from the foremost tubes. It will be manifest that the front casing section incloses the front, sides and top of the 50 tank and tube section, and by reason of its design and finish gives the outward appearance of an integral radiator structure, whereas the casing section may be quickly and easily removed from the tank and tube section so as to expose the latter and permit repairs of the tubes and tanks to be made with greater facility and at less cost than is possible with those integral radiator constructions in which the tube and radiator fins are rigidly united.

I have also provided a back fin section shown in Figs. 5 and 8 composed of a suitable frame 26 carrying fins 27 and adapted to be removably mounted at the back of 60 and in contact with the rearmost circulating

tubes. The upper edge of this frame 26 is retained against displacement by a suitable guide, such as an angle iron bar 28, and the lower end is provided with depending brackets 29 adapted to be secured by bolts 31 to 70 the lower tank. When in operative position, the radiation fins on this section will be held in contact with the rearmost circulation tubes. This back fin section may obviously be easily removed and replaced, and will when 75 in operative position, function as a heat-radiating and water-cooling means.

It is believed that the foregoing conveys a clear understanding of the objects prefaced above, and while I have illustrated but 80 a single embodiment, it should be understood that considerable change might be made in details of construction without departing from the spirit and scope of the invention as expressed in the appended 85 claims:

I claim:

1. A sectional radiator comprising a tank and tube section having an upper and a lower tank connected by vertical circulation tubes, and an outer casing section shaped to fit over the top, front and sides of said tank and tube section and be removably supported thereon and having a front opening and radiation fins across said opening held in contact with the foremost circulation tubes when the outer casing section is in operative position. 90
2. A sectional radiator comprising a tank and tube section, a removable front casing section having radiation fins, and a removable back section having radiation fins. 100
3. A sectional radiator comprising a tank and a tube section having an upper and a lower tank carried by vertical circulation tubes, an outer casing having front, side and top walls covering and removably mounted on the tank and tube section, the front wall having an opening exposing the circulation tubes, and radiation fins carried by the outer casing and disposed across said opening in contact with the foremost circulation tubes. 105
4. A sectional radiator comprising a tank and tube section having an upper and a lower tank connected by vertical circulation tubes and side walls and having a supporting member reaching outwardly from each side wall, and an outer casing section having front, side and top walls, and a supporting member reaching outwardly from each side wall, said outer casing section being adapted to be removably supported on the tank and tube section with its outstanding supporting members seated on those of the latter section, said front wall having an opening, and radiation fins carried by the outer casing across said opening in contact with the foremost circulation tubes. 115
5. A sectional radiator comprising a section having an upper and a lower tank 120
- 125
- 130

- joined by circulating tubes, a front casing section removably mounted on said tank and tube section and having radiation fins in front of said tubes, and a rear section removably mounted on said tank and tube section and having radiation fins at the rear of said tubes.
6. A sectional radiator comprising a tank and tube section having an upper and a lower tank connected by vertical circulation tubes, an outer casing section removably supported on said tank and tube section and having radiation fins held in contact with the foremost circulation tubes, and
- 10 a back fin section interposed between the upper and lower tanks and removably supported in such position with its radiation fins in contact with the rearmost circulation tubes.
7. A radiator of the character described comprising a tank and tube section having an upper and a lower tank connected by circulation tubes and an outer casing covering the front, sides and top of said tank and tube sections, said outer casing having 25 radiation fins held in contact with the foremost circulation tubes, said outer casing being removable as a unit from the tank and tube section.

JOSEPH A. CONRAD.
